UNITED STATES PATENT OFFICE

**CORVAL R. JACKSON, OF INDIANAPOLIS, INDIANA, ASSIGNOR, BY MESNE ASSIGNMENTS,
TO ABBOTT LABORATORIES, OF CHICAGO, ILLINOIS, A CORPORATION OF ILLINOIS**

DESIGN FOR AN ATOMIZER

Application filed September 12, 1930. Serial No. 36,947. Term of patent 14 years.

To all whom it may concern:

Be it known that I, CORVAL R. JACKSON, a citizen of the United States, residing at Indianapolis, in the county of Marion and State of Indiana, have invented a new, original, and ornamental Design for an Atomizer, of which the following is a specification.

The figure is a perspective view of an atomizer showing my new design.

I claim:

The ornamental design for an atomizer as shown.

In witness whereof, I, CORVAL R. JACKSON, have hereunto set my hand at Indianapolis, Indiana, this 8th day of September, A. D. one thousand nine hundred and thirty.

CORVAL R. JACKSON.
